UNITED STATES PATENT OFFICE

ROBERT C. RICHARDSON, JR., OF WEST POINT, NEW YORK

DESIGN FOR A PLATE OR SIMILAR ARTICLE

Application filed March 5, 1931. Serial No. 38,943. Term of patent 14 years.

To all whom it may concern:

Be it known that I, ROBERT C. RICHARDSON, JR., a citizen of the United States, residing in West Point, in the county of Orange and State of New York, have invented a new, original, and ornamental Design for a Plate or Similar Article, of which the following is a specification, reference being had to the

accompanying drawing, forming a part thereof, in which the figure is a plan view of the plate showing my new design.

I claim:

The ornamental design for a plate or similar article substantially as shown.

ROBERT C. RICHARDSON, JR.
